UNITED STATES PATENT OFFICE.

ANNA E. HANNAN, OF ATLANTIC CITY, NEW JERSEY.

FORM-BELT.

1,115,927.

Specification of Letters Patent.

Patented Nov. 3, 1914.

Application filed September 20, 1913. Serial No. 790,830.

To all whom it may concern:

Be it known that I, ANNA E. HANNAN, a citizen of the United States, residing at Atlantic City, in the county of Atlantic and State of New Jersey, have invented certain new and useful Improvements in Form-Belts, of which the following is a specification.

My invention relates to improvements in form belts, and the object of my invention is to provide a belt for shaping or forming the dress or gown at the waist, giving to the garment the natural curve of the body at the waist line and sustaining the strains, relieving the goods thereof.

The invention consists in certain novel features of construction and combinations and arrangements of parts as will be more fully hereinafter described and pointed out in the claim.

In the accompanying drawings: Figure 1 is a view in elevation with parts broken away illustrating my improvements. Fig. 2 is a view in transverse section through the garment and belt at the waist line. Fig. 3 is a broken plan view of the belt, and Fig. 4 is a view in vertical section through the belt and garment at the waist line on the line 4—4 of Fig. 2.

1 represents a dress or gown, and 2 my improved belt composed of inelastic material, which is secured to the inner face of the dress or gown at the waist line by lines of stitching 3. These lines of stitching terminate short of the meeting point of the gown, and short of the ends of the belt, so that the ends of the belt are free for manipulation and may be readily secured together or released.

40 I have illustrated as fastening means ordinary hooks and eyes 4, but would have it understood that I may use any form of fastening device.

The belt 2 is provided throughout its length with a plurality of curved plaits 5, said plaits secured by two lines of stitching 6 and 7, one line of stitching at a right angle

to the belt, and the other line of stitching in an arc of a circle conforming in outline to the outline of the plait. As many of these 50 plaits may be provided as desired to give to the belt a curvature in cross section conforming to the natural curve of the body and compelling the gown to lie smoothly at the waist.

55

At the ends of the belt, straight folds or seams 8 are preferably provided so that the belt at its ends is straight in transverse dimension, but between its ends is curved in its transverse dimension. This is desirable 60 because gowns as ordinarily made have a straight front, but curve at other points throughout the waist line, so that the belt assumes a natural position in accordance with the form of the body, and sustains all 65 of the strains without in any manner wrinkling the garment.

The belt is designed to be permanently attached to the dress or gown, and gives to the gown at the waist line the shape desired 70 without stretching or wrinkling the goods.

Various slight changes might be made in the general form and arrangement of parts described without departing from my invention, and hence I do not limit myself to the 75 precise details set forth, but consider myself at liberty to make such changes and alterations as fairly fall within the spirit and scope of the appended claim.

Having thus described my invention, what 80 I claim as new and desire to secure by Letters Patent is:

A form belt of the character described, having a longitudinal series of curved plaits, each plait held in position by a straight and 85 a curved line of stitching, substantially as described.

In testimony whereof I have signed my name to this specification in the presence of two subscribing witnesses.

ANNA E. HANNAN.
